UNITED STATES PATENT OFFICE.

EDWARD BAGNALL, OF PITTSBURGH, PENNSYLVANIA, ASSIGNOR TO ZOFFER PLATE GLASS MANUFACTURING COMPANY, OF PITTSBURGH, PENNSYLVANIA, A CORPORATION OF WEST VIRGINIA.

GLASS-GRINDING TABLE.

1,198,402.

Specification of Letters Patent. Patented Sept. 19, 1916.

Application filed November 30, 1915. Serial No. 64,245.

To all whom it may concern:

Be it known that I, EDWARD BAGNALL, a citizen of the United States, residing at Pittsburgh, in the county of Allegheny and 5 State of Pennsylvania, have invented certain new and useful Improvements in Glass-Grinding Tables, of which the following is a specification.

My invention relates to improvements in 10 apparatus for grinding, smoothing and polishing plate glass, and it has for its object to provide effective and economical means for cushioning and holding the glass plates upon the upper portion of the rotating 15 table, in connection with the operations performed by the usual superimposed runners and abrasive material.

In carrying out my invention, the rotatable supporting table is provided with 20 means for exhausting the air from its interior, and a plurality of numerous somewhat closely adjacent specially shaped perforating apertures communicating with the interior suction cavity of the table, adapted 25 to support a pervious resilient bedding, upon which the glass plates are laid, whereby to provide for the necessary degree of compression of the bedding and the exhaustion of the air therethrough in effecting a partial vacuum and a resulting holding 30 air pressure.

Preferred embodiments of the invention are shown in the accompanying drawings, in which—

35 Figure 1 is a plan view of the apparatus showing certain of the exposed air circulation cavities, a portion of the bedding, and a portion of the glass plates carried thereby. Fig. 2 is a vertical cross section, indicated 40 by the line II. II. of Fig. 1. Fig. 3 is a detail sectional view, enlarged, showing the action of the apparatus when the table is covered with glass plates. Fig. 4 is a similar view, showing the pervious bedding as 45 composed of a plurality of layers of material, as canton flannel. Fig. 5 is a similar view, and showing a resilient supporting bed interposed between the table and the pervious bedding. Fig. 6 is a view similar 50 to Fig. 2 showing a modified construction, with the accompanying actuating and air exhausting mechanism. Fig. 7 is an en-

larged vertical sectional view of the hollow supporting mast and the surrounding packed air circulation collar, taken on the 55 line VII. VII. of Fig. 8. Fig. 8 is a cross section on the line VIII. VIII. of Fig. 7.

The rotatable glass supporting table A is preferably made of an upper wall 2 and a lower wall 3, providing an interior air 60 cavity 4. The table is preferably made in a plurality of sections and divided at the line 5, the sections constituting units of the complete table connected, as shown, and providing for the continuous circulation of the 65 air throughout its entire interior by means of the central common rotatable air conduit or hollow spindle 6. Said spindle may be connected with the interior of the table in any suitable manner, operating as a hollow 70 mast which may act as the main supporting stem or column of the table, and which may be provided with an actuating drum, pulley or gear wheel 7. Said gear is rigidly incorporated with the table or its central mast 75 in any suitable manner, as shown, preferably resting upon roller or ball bearings 8, and being driven by a gear wheel 9, or in any other suitable manner, as will be readily understood.

80 The central hollow spindle 6 is mounted in any suitable packed bearing, as indicated, and is in constant communication by suction pipe 10 with any suitable air exhausting mechanism. By this arrangement it will be 85 readily seen that the interior of the table is in suction communication with such exhausting means at all times during its operation.

The upper wall 2 of the table, which is 90 level and substantially smooth, is provided with numerous somewhat adjacent coniform-shaped openings 11 flaring outwardly and providing a series of cup-shaped downwardly tapering cavities throughout the entire supporting area of the table, each of which is in communication with the main interior cavity 4 by means of a reduced communicating port 12.

95 For the purpose of providing a supporting bed for the plate glass, I lay completely over the entire area of the table A, and covering all of the cavities 11, a bedding 13 consisting of canton flannel, hair felt, cloth,

or other suitable pervious material having sufficient body to provide a compressible supporting cushion for the plates 14. Surrounding the periphery of the table and closing the exposed edges of bedding 13 to the atmosphere, after the plates 14 are laid, I may, if desired, provide a surrounding packing 15, which may be of plaster of Paris or other suitable material easily applied or removed, and which will effectually seal the edges of the bedding 13 against access of air, upon creation of the suction vacuum. The packing 15 is however, not absolutely necessary. The table being thus covered and the plates being in position, exhaustion of the air from cavity 4 will create a suction of the air through the pervious bedding 13 and cavities 11 and ports 12, resulting in a corresponding external air pressure, which 20 will bind the plates 14 firmly upon the bedding.

At locations corresponding to the openings 11, the bedding will be somewhat depressed under outside air pressure, as indicated at 16, thereby providing collecting pockets for the air which is exhausted from beneath the entire surrounding area of the plates wherever they are in close contact with the other compressed supporting portions of the bedding. By this means the exhaustion of the air is facilitated and its constant action in maintaining suction and resulting compression upon the plates is maintained.

35 The pervious bedding layer 13 may be in one continuous piece, laid across the entire surface of the table, but if necessary, it may be in two or more parts, having tightly contacting edges, whereby to avoid undue leakage, and it will thus serve to provide a practically uniform, level, resilient support for the glass plates.

In practice, I have used a plurality of circular layers 13^a of canton flannel, made of 45 normal widths of material, laid edge to edge and stitched, as indicated at 13^b, the seams thus not increasing the normal thickness, and preferably laid across the seams of the next under and upper layer, as clearly 50 shown in Fig. 1. Spaces between the plates 14 may, if desired, be filled with narrow strips of wood, plaster of Paris, or other suitable sealing material, as is commonly done in ordinary bedding of the glass, without, however, allowing any of the plaster to 55 accumulate beneath the plates or to interfere with the porosity of the bedding. The bedding may be soaked with water, if desired, or merely damped or used dry, depending upon the conditions present or the material used. I have also used oil in treating 60 the flannel layers with good success, the oil tending to add to the resistance of the flannel to passage of moisture, and increasing 65 its flexibility. The degree of suction or

70 maintenance of the vacuum may be readily controlled within the limits of the air exhausting means employed, and the thickness of the bedding, its resiliency and various other qualities or other different details of construction or utilization of the invention may be variously changed or modified by the skilled mechanic.

In Fig. 5, I show a supporting mat or pad 75 17 of rubber or other suitable somewhat resilient material having a flat under and upper surface, and a series of transverse openings 18 corresponding to and registering with the suction openings 11. By this means I prevent the injurious effect of inequalities in the surface of the table and retain the full advantage of the upper cushion of flannel 13^a, as described. Said figure also shows the edges of the pervious bedding as exposed, the suction being ordinarily 85 ample to overcome any lateral leakage.

In Fig. 6 the several parts of the table and its driving mechanism are the same as above described, indicated by corresponding numerals primed, the hollow mast 6' also having a supplemental bearing 19 and the gearing being driven by a motor 20 and suitable intervening gearing 21, 22. Surrounding the mast 6' and forming a rotatable part with it is an embracing collar 23 through 90 which extends into the hollow interior of the mast one or more communicating nipples 24. Collar 23 is provided with laterally extending annular flanges 25 which extend into receiving grooves 26 of an outer embracing two-part stationary collar 27, having packing gaskets 28 and packing rings 29 adapted to be tightly compressed against flanges 25 and thus effectually pack the rotatable collar 23 within the stationary collar or hub 27. Between flanges 25 is an annular cavity 30 thus 100 in constant communication with the interior of the hollow mast, and also in communication with the air exhausting mechanism by pipe 10'. Said pipe leads to a vacuum tank 110 31 with an intervening by-pass pipe 32 leading to a water collecting tank 33 having a valve controlled exhaust pipe 34, for collection and disposal of any water which may 115 find its way to the suction pipe. An air pump 35 is connected by pipe 36 with the vacuum tank 31, which is also provided with a vacuum gage 37.

The advantages of the invention will be 120 readily understood and appreciated by all those familiar with the construction and operation of glass grinding and polishing mechanism. It obviates the necessity of the usual cementing or other laborious and expensive methods in vogue for holding the 125 glass plates to the table, providing for their easy and quick removal or reversal upon admission of air to the interior; it obviates the danger of breakage incident to the placing of the glass plates directly upon the metal 130

surface of the table, and it provides a certain degree of cushioning action beneath the rotating superimposed runners, while compensating for any unevenness or inaccuracy in the plane of the table.

5. What I claim is:

1. A rotatable glass grinding table having a hollow interior and a plurality of adjacent circular upwardly diverging openings 10 through the upper wall of the table, means for exhausting the air from the hollow interior, and a superimposed porous bedding of compressible material.
2. A rotatable glass grinding table having 15 a hollow interior and a plurality of adjacent circular upwardly diverging openings through the upper wall of the table, means for exhausting the air from the hollow interior, a superimposed porous bedding of 20 compressible material, and a surrounding peripheral air sealing covering for the edges of said bedding.
3. A rotatable glass grinding table having a hollow interior and a plurality of adjacent 25 openings through the upper wall of the table, means for exhausting the air from the hollow interior, a layer of impervious material on the surface of the table having openings registering with the table open-

ings, and a superimposed bedding of compressible material.

4. In a rotatable glass supporting table of the class described having an interior vacuum cavity and an upper supporting wall provided with a plurality of adjacent upwardly flaring transverse openings communicating through diminished openings with the interior; the combination with said upper wall, of a layer of compressible porous material, and glass plates laid thereover.

5. In a rotatable glass supporting table of the class described having an interior vacuum cavity and an upper supporting wall provided with a plurality of adjacent upwardly flaring transverse openings communicating through diminished openings with the interior; the combination with said upper wall, of a layer of compressible porous material, glass plates laid thereover, and a surrounding sealing material inclosing the 50 peripheral edges of the bedding and glass plates and preventing the entrance of air.

In testimony whereof I hereunto affix my signature in the presence of two witnesses.

EDWARD BAGNALL.
